E. F. HATHAWAY

TUFT TUBE ATTACHING MEANS FOR TUBE FRAMES

Filed Dec. 5, 1923

Inventor:
Edgar F. Hathaway

by
Geo. N. Goldard, atty.

UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

TUFT-TUBE-ATTACHING MEANS FOR TUBE FRAMES.

Application filed December 5, 1923. Serial No. 678,659.

To all whom it may concern:

Be it known that I, EDGAR F. HATHAWAY, a citizen of the United States, and resident of Wellesley, in the county of Norfolk and

5 State of Massachusetts, have invented certain new and useful Improvements in Tuft-Tube-Attaching Means for Tube Frames, of which the following is a specification.

This invention relates to tube frames, 10 such as are used in the art of tuft weaving, and is intended to provide a simple and convenient construction by which the tuft tubes, which receive and guide the individual tuft elements from the yarn-spool, may be quickly and conveniently attached and detached 15 from the tube frame-carrier-bar.

As is well known to those skilled in this art, it is often necessary to replace or substitute new tuft tubes for those ordinarily 20 placed on the frame, and to this end the invention comprises, generally speaking, the combination with a longitudinal carrier-bar, of a tuft tube carrying and attaching strip provided at its opposite edges with projecting tongues or attaching members adapted 25 to interlock the cooperating portions of the carrier-bar structure in order to quickly attach or detach a series of tuft tubes which are firmly secured in parallelism to the outside face of said attaching strip. These 30 and other features of the invention will be described in detail in the following specification and will be defined in the claims hereto annexed.

35 In the accompanying drawings:

Figure 1 is a front elevation showing a portion of a tube frame of usual construction with my improved attaching means applied to the carrier bar.

40 Figure 2 is a cross section through the carrier bar showing a tuft tube in elevation.

Figure 3 is a bottom plan view showing the underside means for securing the attaching plate to the carrier bar.

45 In the practice of my invention, according to the form illustrated in the drawing, the longitudinal carrier bar 1, is preferably of tubular or hollow construction, and is secured in any suitable manner to the chain-engaging hangers 2 and 3 with which is as-

sociated a spool bearing bracket 4, for rotatably supporting one end of the yarn-spool (not shown herein).

At any desired intervals along the front face or wall of the carrier-bar I provide 55 apertures or openings 1^a for the reception of retaining or locking tongues, presently to be described.

The attaching strip by which the tuft tubes are carried and releasably secured to the carrier-bar, comprises a longitudinal plate 5, in this case bent into angular form to lie against two adjacent faces of the carrier bar, namely, the front and the bottom faces considered with reference to the position of the carrier-bar when suspended downward from the carrier chains. This attaching strip, near its upper edge, is outwardly bowed to form a raised rib 5^c which forms both a stop shoulder for positioning and aligning the parallel tuft tubes which are soldered thereto, and also serves as a protective ledge to prevent the scraping or chafing of the yarn against the sharp intake edge of the tuft tube as the yarn is drawn through the latter. 75

At its extreme upper edge the attaching strip 5, is provided with plural tongues 5^a so shaped as to permit their insertion through the apertures 1^a in the carrier bar 80 to form an engaging or interlocking tongue whose outward thrust is sustained by the wall of the carrier bar adjacent to said aperture.

At its opposite edge the attaching strip 85 is provided also with a series of short projecting tongues 5^b arranged at any desired intervals apart and adapted to project through cooperating apertures 6^a in a yielding or spring-locking plate 6, which is soldered or otherwise fastened to the bottom portion of the carrier-bar, it being of course understood that the apertures 6^a, in the retaining or locking plate 6, are positioned to register with the projecting tongues 5^b on 90 the attaching plate 5. As is clearly indicated in Figure 2, the free edge of the resilient plate 6 is bent slightly away from the bottom wall or face of the carrier-bar so as to allow the tongues 5^b to be automatically 95 100

sprung into the openings by pressure transversely of the bar, which forces the free edge of the plate 6 outwardly until the tongues spring into the apertures 6^a, it being understood that the tongues 5^a have previously been inserted through the apertures 1^a, preparatory to thus interlocking the attaching strip firmly but releasably to the carrier bar.

With the above described construction there are no screws to manipulate or get lost, and a series of parallel tuft tubes of any desired number, carried on their attaching plate to which they are soldered or otherwise secured, may be instantly secured to and removed from the carrier-bar without the necessity of taking the tube frame out of the loom or away from the carrier chains.

What I claim is:

1. In a tube frame for tuft weaving, the combination with a hollow carrier-bar, a tube attaching and supporting strip whose upper longitudinal edge is provided with attaching tongues formed to penetrate openings in the wall of the carrier-bar to form releasable engagement therewith, the opposite longitudinal edge of said strip being provided with locking members having releasable interlocking spring connection with the outside of the carrier-bar, and a plurality of parallel tuft tubes secured to said attaching strip, substantially as described.

2. In a tube frame for tuft weaving, the combination of a longitudinal carrier-bar, a tuft tube carrying and attaching strip extending longitudinally of the bar and provided at its top and its bottom edges with projecting members formed to be releasably interlocked with external cooperating retaining means secured to the underside of the carrier-bar, by which the strip carrying the tuft tubes is firmly secured in operative position on the bar by a quick detachable engagement, substantially as described.

3. In a tube frame for tuft weaving, the combination of a longitudinal carrier bar, a tuft tube carrying strip provided at its opposite edges with projecting locking members, one set of locking members being arranged to penetrate receiving orifices in the front wall of the bar, the other set having releasable interlocking engagement with a cooperating external resilient keeper located on the underside of the carrier-bar which yields to allow the attaching strip to become interlocked and to become released therefrom, substantially as described.

4. In a tube frame, the combination of a longitudinal carrier-bar provided with a series of tongue-receiving apertures in one face, a retaining strip secured to next adjacent face of said bar and having tongue-receiving apertures therein, and a tube-carrying attaching strip, a series of tuft tubes secured to said strip in parallelism with one another, said strip having at its opposite

edges series of retaining tongues arranged to be releasably engaged with the carrier bar and with said retaining strip to permit quick attachment and removal of the tube carrying strip, substantially as described. 70

5. In a tube frame for tuft weaving, the combination of a longitudinal carrier-bar provided with series of tongue-receiving apertures on two adjacent faces, a tube-carrying and attaching strip of angular cross section transversely of its length with tongues on its opposite edges arranged to penetrate and interlock with the respective apertures, thereby holding the tube-carrying strip securely to the carrier-bar while permitting its easy detachment therefrom, substantially as described.

6. In a tube frame for tuft weaving, the combination of a carrier-bar, a longitudinally extending strip, a series of parallel tuft-tubes secured thereto, said strip being longitudinally bent to form two angularly disposed portions lying respectively against the front and bottom faces of the bar, each portion being formed at its edge with members adapted to form releasable interlocking connection with the bar to detachably secure the tube-carrying strip in position, substantially as described.

7. A tuft-tube carrying strip comprising a longitudinal plate of angular cross-section transversely of its length having one longitudinal edge provided with locking tongues adapted to interlock with corresponding recesses in one face of a carrier-bar and having its other longitudinal edge formed to interlock with an external retaining member secured to another face of the carrier-bar, substantially as described. 95

8. Attaching means for detachably securing a row of tuft tubes to the carrier-bar of a tube frame embracing two longitudinal attaching strips one of which is secured to the outside of the carrier-bar, the other strip forming a tube-carrying member provided with bar-penetrating and engaging tongues at its upper longitudinal edge and being formed at its lower longitudinal edge to have releasably interlocking spring engagement with said first mentioned strip, whereby the row of tuft tubes is secured to the carrier-bar by a quick detachable connection, substantially as described. 105

9. Attaching means for securing a row of tuft tubes to a tube frame carrier-bar by a quick detachable connection embracing in combination with a carrier-bar a pair of external attaching strips extending longitudinally of the bar and having their adjacent edge portions formed to have releasable spring interlocking engagement with each other, one of said attaching strips carrying a row of tuft tubes and having at its upper longitudinal edge means for detachably engaging the carrier bar. 120

10. Means for securing tuft tubes to a tube frame carrier-bar embracing in combination with the carrier bar, a longitudinal tuft tube carrying strip whose upper edge portion is formed to hook into recesses in the center bar, and a spring keeper secured externally to the carrier-bar and formed to

releasably engage the adjacent edge of the tuft tube carrying strip to hold the latter firmly but detachably against the carrier-bar, substantially as described. 10

In witness whereof, I have subscribed the above specification.

EDGAR F. HATHAWAY.
